UNITED STATES PATENT OFFICE.

FREDERIC E. BALDWIN, OF NEW YORK, N. Y.

MINER'S LAMP.

1,101,982.

Specification of Letters Patent. Patented June 30, 1914.

Application filed May 22, 1913. Serial No. 769,142.

To all whom it may concern:

Be it known that I, FREDERIC E. BALDWIN, a citizen of the United States, and a resident of Richmond borough, New York city, and 5 State of New York, have invented certain new and useful Improvements in Miners' Lamps, of which the following is a specification.

In constructing acetylene lamps in general 10 and particularly lamps for use in mines, it is desirable that the flow of water to the carbide be as constant as possible. It is also desirable that this constant water flow should be maintained automatically. It has been 15 found in practice that it is impossible to adjust the flow of water, manually, so that at all times just the desired amount of water shall be constantly delivered to the carbide. This result has been in part obtained by the 20 use of a pipe of suitable interior diameter and restricting the flow of water through this pipe by inserting a wire of suitable outside diameter to permit of only such flow of water through the pipe as may be required to supply gas to the burner. When 25 manufacturing these lamps in large quantities however, it has been found impossible to proportion the two diameters so that the flow of water should be even approximately 30 correct. This difficulty arises from the necessity of using a fairly long water tube in order to maintain the desired water column pressure and any slight deviation in the diameters of the wire and tube cause a very 35 marked variation in the flow of water, owing to the amount of friction on the water induced by the length of the restricted water tube. I overcome this difficulty by having only one portion of the device restricted, the 40 other portion of the device permitting of a greater flow of water, thus offering less friction to the water passing through than the restricted portion.

When a water tube is closely restricted its 45 full length, said tube affording part of the water column pressure and an occasional excess of gas occurs in the lamp, this friction of the water in the tube largely prevents the excess gas from flowing back through the 50 water tube and escaping into the air with an offensive smell. In fact it has been found by water gage test that owing to this friction, where the lamp is operated under a $2\frac{1}{2}$ " water column pressure, the gas will 55 frequently not escape out of the lamp up through the water tube before a 4" or 5"

water column pressure is obtained inside of the lamp. In constructing my improved water tube it is therefore necessary that the enlarged portion shall be only slightly enlarged so as not to lose this value of the water friction, otherwise any slight excess of gas will escape up through the water tube and into the air with an offensive smell, but which will be burned if the friction in the water column is still maintained.

I also find when a water tube as above constructed, is immersed directly in the mass of carbide, that by cutting the exit orifice of the water tube at an angle, a steadier flow of water is maintained, as by thus increasing the delivery surface of the orifice it takes longer for the carbide so to clog up the orifice that it has to be broken up by the agitation of the stirring or poking wire.

It is to be understood that the desired restriction can be obtained either by drilling a portion of the tube larger or by making a portion of the stirring or poking wire smaller.

In the accompanying drawing I have shown, in vertical section, chiefly, a miner's lamp equipped with my improved means for regulating and equalizing the water flow.

As shown the lamp is formed with an upper portion A, and a lower portion B, separated by the partition *a*. The water is held above the partition and the carbide below.

C, indicates a reflector, and D, a burner tube.

It is understood that the form and construction of the lamp is not essential to the use of my present invention but may be of any of the ordinary and usual makes, or of special design if preferred.

The feed tube E is of usual construction except that at its top portion *e* for a short distance, the bore of the tube is somewhat contracted, so that the flow of water past the stirring rod F, will be exactly that which is required to supply the carbide constantly and automatically with the right amount of water required for the proper generation of gas as long as the tube is open. The length of the water tube is greater than the depth of the water tank, from which it results that variations in the depth of the water in the tank causes only small variations in the water column pressure. It is of course understood that the tube E, hangs downward from the partition *a*, and is open into the water reservoir except when closed by a suitable

valve. As explained above the stirring rod F, is usually run through this feed tube and caused to project above the top of the lamp where it is bent over as shown to form a sort of handle by which it can be lifted and revolved to stir up and poke the carbid which surrounds the bottom of the feed tube. The contraction of the bore of the feed tube at its upper end is not for the purpose of entirely choking the tube but merely to form a passage around the stirring rod, as nearly as possible fitted to the quantity of water as required for a constant automatic supply.

As a valve for closing the top of the tube

15 E, I have shown a telescoping tube G, which is lifted away from the tube E, to let the water flow and pushed down upon it to the position shown in the drawing to cut off the water flow. This telescoping valve I do not 20 claim here because I am making it the subject of a separate application Serial No. 768,775, filed May 20, 1913, nor do I claim the form of coupling shown in the drawings 25 whereby the upper and lower portions of the lamp are connected, this subject matter being claimed in my application Serial No. 768,200, filed May 17, 1913.

I claim;

1. A miner's lamp provided with a water 30 feeding tube and a rod located longitudinally therethrough; the passage between the exterior of said rod, and the inner wall of said tube being restricted during only a portion of its length to permit the quantity 35 of water required for the proper operation of said lamp.

2. A miner's lamp provided with a water tank, a carbid container, an elongated water feeding tube and a rod extending there- 40 through, the passage between said rod and tube being constricted for a short distance at its upper end so that only so much water

will flow as will supply gas for the desired flame, and being larger throughout the remainder of its length.

3. A miner's lamp provided with a water tank, a carbid container, an elongated water feeding tube and a rod extending there- 45 through, said rod being of substantially uniform diameter and the upper end of the bore of said tube being slightly more constricted than the remainder thereof, the passage along the rod at the restricted portion being such as will permit only enough water to flow to generate sufficient gas for the de- 50 sired flame.

4. A miner's lamp provided with a water tank, a carbid container, an elongated water feeding tube and a rod extending there- 55 through, the passage between said rod and tube being constricted for a short distance at its upper end so that only so much water will flow as will supply gas for the desired flame, and being slightly larger throughout the remainder of its length, the length of the water tube being greater than the depth of the water tank.

5. A miner's lamp provided with a water tank, a carbid container, an elongated water feeding tube and a rod extending there- 60 through, said rod being of substantially uniform diameter and the upper end of the bore of said tube being slightly more constricted than the remainder thereof, the passage along the rod at the restricted portion being such as will permit only enough water to flow to generate sufficient gas for the de- 65 sired flame, the length of the water tube being greater than the depth of the water tank.

FREDERIC E. BALDWIN.
